UNITED STATES PATENT OFFICE.

JAMES MCGILLIVRAY, OF SACRAMENTO, CALIFORNIA.

REVETMENT.

1,148,915.

Specification of Letters Patent.

Patented Aug. 3, 1915.

Application filed May 7, 1914. Serial No. 837,060.

To all whom it may concern:

Be it known that I, JAMES MCGILLIVRAY, a citizen of the United States, residing at Sacramento, in the county of Sacramento and State of California, have invented certain new and useful Improvements in Revetments, of which the following is a specification.

This invention relates to revetments especially designed for the protection of levees and the like by means of reinforced concrete and contemplates a monolithic structure made *in situ* above the water level and combined with a group of concrete blocks united together to cover the levee below the water level.

The invention therefore consists in the structure and combination of parts for the specified purpose substantially as hereinbelow set forth and claimed.

To fully disclose the invention and its application reference is made to the accompanying drawings which form a part of this specification. Therein—

Figure 1 represents in vertical section on line 1—1 of Fig. 2 a levee protected by the improved revetment; Fig. 2 is an elevation of a portion of said revetment; and Fig. 3 represents in perspective one of the revetment units or blocks of reinforced concrete used below the water level.

The reinforced concrete revetment units patented by me Sept. 29, 1914, and on which other patents are pending, Serial No. 796,579 October 6/13; Serial Numbers 882,038 and 882,039 Mar. 2/14 and Serial No. 839,628 May 19/14, are well adapted for covering that portion of the embankment below water, for they consist of rectangular blocks which may be formed where convenient and transported to the place of use. They are also provided with holes at their ends through which suitable ties, typified at 14, may be passed for connecting them together. They also have grooves along their ends in which cables may be confined by the act of tying the blocks together. This provides for securing such blocks to cables and lowering them from a barge, or down the embankment, to the desired distance below the water level, the cables having first been connected at their lower ends to a metal strip, indicated at 15, which forms a washer common to all the cables in each longitudinal section of revetment. Such revetment units

are typified at 4 in Figs. 1 and 2 and shown individually in Fig. 3. The tie holes are at 5 and the cable grooves at 6. The group of such units is extended above the level of the water, indicated at 16, at the time of laying, the cables being preferably anchored at the top of the embankment in any suitable manner as indicated at 7 by attaching them to "dead men" or other forms of anchors. The cables are represented at 8. The embankment above the group of blocks is then covered with concrete in any convenient manner and to the desired extent and to a depth preferably equal to the thickness of the blocks which it adjoins. A monolithic structure 4' is thus formed in place and it is reinforced by the cables 8 which it also covers and helps to hold in place. To locate the cables in the body of the monolithic structure T's may be used as desired, the same being typified at 9.

Other reinforcement of the monolithic structure may be added transversely of the cables. Such may consist of rods indicated at 10.

It is also desirable in some latitudes to provide expansion joints in the monolithic structure. Such joints are indicated at 11 as unfilled and at 12 as filled by any suitable yielding material such as an asphaltum compound. In latitudes where there is no great variation in temperature the expansion joints will be omitted.

The concrete blocks used at the lower edge of this combined revetment are preferably reinforced as indicated at 13 in Fig. 3. Thus a revetment is formed of reinforced concrete throughout and one which can be laid rapidly and which will hold its place to the perfect protection of the levee or embankment.

The invention claimed is:—

In a revetment the combination of reinforced concrete blocks located below the water level, reinforced monolithic structure above the water level and anchoring means for said blocks extending through the monolithic portion and forming part of the reinforcement therefor.

In testimony whereof I have affixed my signature in presence of two witnesses.

JAMES MCGILLIVRAY.
